UNITED STATES PATENT OFFICE.

ALBIN WINKLER, OF PETROGRAD, RUSSIA, ASSIGNOR OF ONE-HALF TO ROBERT LEIBFRIED, OF PETROGRAD, RUSSIA.

KNITTING-MACHINE.

1,165,478.

Specification of Letters Patent. Patented Dec. 28, 1915.

Application filed August 5, 1913. Serial No. 783,196.

To all whom it may concern:

Be it known that I, ALBIN WINKLER, a subject of the Emperor of Russia, residing at Kolpinskaia 27, Petrograd, Russia, have 5 invented new and useful Improvements in Knitting-Machines, of which the following is a specification.

The present invention has reference to a knitting machine employing bearded 10 needles, and having two needle rows, for making flat or tubular fashioned goods.

The machine is, according to this invention, furnished with two loop sinking devices for the two needle rows, which devices 15 can be adjusted to change their position in relation to the needle rows whereby the formation of the meshes may be carried out by either of the needle rows, or by both.

In the production of flat goods, *i. e.* plain 20 work on one needle bar, the yarn threads are always looped on one and the same row of needles; but in making tubular (plain circular) goods, the looping of the yarn threads is performed on both needle rows 25 alternately; and in the case of reversible goods the mesh is made, in general, on one needle row, though it can be made on both rows alternately.

In order to admit of the already mentioned changes in the position of the loop sinking devices in relation to the needle rows being effected, the loop sinking devices—which will hereinafter be termed the swing heads—are made capable of tilting. 35 To this end, the said swing heads are arranged parallel to and facing each other, in, for example, a box-like frame, which is rotatably mounted so that it can swing on pivots. When moved in this manner, one 40 swing head moves away from its needle row, while the other swing head approaches so closely to its corresponding needle row as to be able to work in conjunction therewith.

The term swing head means the loop 45 sinking device required for each oppositely situated needle row. Said device consists particularly of the jack sinkers mounted in such head, the falling bar, the jacks, the slurcocks, the slurcock bar, and the slurcock 50 race. The present machine accordingly consists of two rows of jack sinkers for the two needle rows, together with, in each case, one loop sinking device composed of the members previously specified. In addition,

two known narrowing devices are provided 55 for narrowing the goods.

In the accompanying drawings, which illustrate a convenient form of a machine modification of this invention:—Figure 1 represents an end view of the machine; Fig. 2 60 is a side elevation, and Fig. 3 is a plan, with the upper portion of the machine removed. Fig. 4 shows on a larger scale, the method of transmitting movement to the boxes carrying the two swing heads; Fig. 4 shows, as 65 a detail, the slurcock pawl shown in Fig. 4; Fig. 4^b is an elevation of the thread guide. Figs. 5, 6, 6^a and 6^b illustrate the loop sinking process; Fig. 6^c is a plan of the portion of the mechanism shown at the top of Fig. 70 6. Fig. 6^d is an elevation of parts shown in Fig. 6^c. Figs. 7, 7^a and 7^b illustrate the displacement of the shaft; Fig. 8 illustrates the manner in which the needle bars act. Fig. 9 shows the transmission of motion to 75 the sinkers; Fig. 10 shows the transmission of motion to the pressers. Figs. 11 and 11^x show (on a larger scale) respectively the upper part and lower part of a vertical section through the machine. Fig. 11^a illustrates the stroke of the falling bar; Fig. 11^b shows the transmission of the requisite motion thereto; Fig. 11^c illustrates the common stroke of the falling bar and swing 80 head during the turning of the box when 85 tubular goods are being made; Fig. 11^d shows the same operation when producing flat ware. Figs. 11^e and 11^f are detail 90 views of the slurcock pusher, to illustrate the changing over. Fig. 11^g shows the swing head in the opposite position to that shown in Fig. 11. Fig. 12 illustrates the operation in narrowing.

The machine illustrated in the drawings has two swing heads, in which the jacks 101 95 and 102, as well as the other loop-sinking members, are mounted. In knitting machine construction these loop-sinking devices in general are termed "heads" especially in machines of the Cotton type. These two 100 heads are built into the box 13, which is adapted to be turned about the axis 18, as hereinafter described, so as to change the position of the heads with relation to the frame needles, as can be seen by comparing 105 Figs. 11 and 11^g.

The two needle bars 59 and 60 (Fig. 11) which are provided with bearded needles 59^a

and 60^a respectively, slope toward each other after the manner of a straight knitting machine, and are adapted to move up and down over inclined surfaces 16 and 17 of a trestle frame 18, in order that they may describe the requisite forward and return strokes for making the loops and knocking them off. Above the said two needle bars lie the parallel swing heads, which consist essentially of the jacks 101, 102, the sinkers 99 and 100, the slurcock boxes 150, 151 running on the guide tracks 109, 110. In the position shown in Fig. 11 the sinkers 99 coact with the needle bar 59, while in the position shown in Fig. 11^a the sinkers 100 coact with the needle bar 60. The machine is also provided with two pressers 74 and 75 (Fig. 11) for the needles 59^a and 60^a, the thread-guide 131 with the bar 20 and the known narrowing devices 119 and 120 (Fig. 12).

In a manner similar to a Cotton knitting frame, but doubled, there are provided for operating the working tools of the present knitting machine, two cam shafts 2 and 3, a sinker-lever shaft 84, (Fig. 11^a), two needle-lever shafts 51 and 52 (Fig. 8), two tickler-lever shafts 123, 124 (Fig. 12), a presser-lever shaft 65 (Fig. 11^a), a change-motion shaft 6 and a bottom shaft 12 (Figs. 1 to 3). The rotating cam shafts 2 and 3, which are connected together by pinions 4 and 5, are rotated by means of any suitable driving mechanism (not shown in the drawing) which is caused to engage with the pinion 4.

In the cams on the shafts 2 and 3 the curve for producing the requisite operative movements of the members subjected to its influence, extends half way around the circumference, and is duplicated, there being one such curve on each half of the cam. This enables work to be carried on either of the two rows of frame needles alternately, or on one and the same row of needles continuously, without changing the speed of the shafts 2 and 3.

The loop-forming device is operated by an arrangement similar to that used in the Cotton knitting machine. A pair of cone wheels 28, 29 (Figs. 2, 3, 5 and 6) set in rotation by the shaft 2, cause the sinker cam 26 to rotate, this acting on rollers 148 and 149 carried by a bar 152 which is suspended from a bar 33 by means of arms 154, 155 loose on said bar 33. The bar 152 is moved endwise by the sinker cam 26 (the arms 154, 155 moving therewith to and fro on the bar 33) and imparts a corresponding rocking movement to a lever 27 which is fulcrumed at 27^a and connected with the arm 155 by means of a bolt 156. The lever 27 carries with it the sinker bar 19, on which is loosely supported a driver 157 (Figs. 6, 8^a and 6^a) that is connected by bolts 158, 159 with bars 117, 118. The bars 117, 118

are respectively connected with the guide boxes 150 and 151 of the slurcocks 150^a, 151^a. When the sinker bar 19 is moved longitudinally by lever 27 as described one or the other of two rings 160, 161 adjustably secured on said bar will come into contact with the driver 157 and by the connections just referred to effect an adjustment of the guide boxes 150, 151 and the slurcocks 150^a, 151^a on the guide bars 109, 110 therefor. Simultaneously the thread guide 131 (Fig. 11) will be shifted by means hereinafter particularly pointed out. At the termination of the movement thus caused by the action of ring 161 on the driver 157, the sliders 115, 116 of the slurcock pushers will be brought into contact with bell cranks 22, 23 and by the contact of the lower of said bell cranks with a knocker 25 the slurcocks will be caused to extend in opposite directions vertically. The operating device for the latter is explained later on.

The machine works in the following manner:—

1. *Plain tubular goods.*—Before commencing a fresh row of loops, the box 13, with the two swing heads, is arranged in the horizontal position, shown by dotted lines in Fig. 11^a, which position will be hereinafter called the bottom position. In this position the rollers 10 and 11 of an anchor shaped member 7 (Fig. 4), which is temporarily in a vertical position, make contact with juxtaposed slanting surfaces of cams 31 and 32 on the shafts 2 and 3. The needle bars 59 and 60 (Fig. 8) are in their lowest (knocking off) position, while the cams 53 and 54 made contact by means of the most prominent portions of their peripheries, with the rollers of the levers 55 and 56 which operate the needle bars. In the aforesaid bottom position a sinker cam 85^a (Fig. 9) is in contact, by means of its prominent peripheral section 85^a (Fig. 9), with the roller of a lever 86, mounted on a shaft 84, so that a lifting surface 87 (Figs. 11^a, 11^c) is raised, together with bars 88 and 89 (Figs. 11 and 11^a) and the swing-head push bars 92 and 93 which bear against said surface by means of set screws 113, 114, 121, 122 (see Figs. 11, 11^a, 11^c, 11^a). By this means the two swing heads and their falling bars 90 and 91 (Figs. 11 and 11^a)—as also the sinkers 99 and 100 situated thereon—are raised to the top position (Fig. 11^c, dotted lines). A presser cam 66 (Fig. 10) mounted on the shaft 2, assumes such a position—in the said bottom position of the members—that its extension 66^a is 135° behind the position shown in Fig. 10, in a direction opposite to that indicated by the arrow. The sinker cam 26, which is shown in its left hand position in Fig. 6, is on the right when the members are in the said bottom position, while the sinker lever 27, instead of being in the inward position

shown in Fig. 6, has also swung to the right under the action of said cam. If now the shafts 2 and 3 be turned through 15° in the direction of the arrow in Fig. 4, out of the 5 said bottom position, then the operating members take up the position represented in Fig. 4, in which the raised portion of the cam 32 makes contact with the roller 11, and the recessed portion of the cam 31 makes 10 contact with the roller 10. The anchor 7 is consequently moved in toward the shaft 2, that is to say toward the right, and this movement is transmitted through a quadrant 9 and pinion 8, on a shaft 6, and also 15 through a bell-crank lever 135 with draw bars 14 and 15, to the box 13 which also turns over toward the right. By this tilting movement of the box 13 toward the right, the slurcock pushers 115 and 116 20 (Figs. 11, 11') are displaced by means of one of the slurcock bell cranks 22 and 23 (Figs. 4, 4^a and 6^d)—connected together by means of a shaft 24—coming against its corresponding striker 25 (Figs. 1 and 4), in such 25 a way that the slurcocks are reversed, the slurcock of the one row of sinkers being thrown out of action and that of the other row of sinkers thrown into action. At the same time the right hand swing head sinks 30 in consequence of the push bar 92 (Fig. 11), which carries it, sliding (by means of the roller 92^a (Figs. 3, 11^a, 11^c and 11^e) mounted on its end) over the concentric track 107 of a heart-shaped member 94 (Fig. 11^x). 35 The push bar 88, which carries the falling bar 90, and whose roll 88^a leaves its path on the outer edge of the heart-shaped member 94, as the latter has made a rotation through 15° , is caught by the lifting surface 87 and 40 descends with same, since the cam 85 of the shaft 3 (Figs. 9 and 11^c) glides by the roller 86^a on the lever 86 up to the point marked *x* in Fig. 11^b. On the shafts 2 and 3 being turned through another 30° the lever 86 of 45 the shaft 84 (Fig. 11^b) swings down into its lowest position, corresponding to the position of the cam 85 of the shaft 3. This movement is followed by the lifting surface 87, together with the push bar 88 and the 50 falling bar 90 (Fig. 11^c). The right hand swing head, however, cannot follow this movement, since its push bar 92 is resting, by means of its roller 92^a, against the track 107 on the heart-shaped member 94 (Fig. 11^x). 55 At the same time the left hand swing head and the corresponding falling bar are held in the top position by means of the heart-shaped member 94. By means of its roller 55^c, the needle bar lever 55 of the shaft 51 (Fig. 8) makes contact with the recess in the needle cam 53 of the shaft 2, so that the needle bar 59 is raised into the top position by means of its push bar 57. The 60 needle bar 60 is kept down in its bottom position (Fig. 8) by means of a draw bar 61 of the anchor 7, engaging with the arm 56. In this way the anchor 7 with its draw bar 61 brings one cam-half out of action, alternately in front and rear, and causes the working movement necessary for producing 70 tubular goods to be performed. A further rotation of the shafts 2 and 3 through 60° causes the formation of the meshes. As already mentioned, the sinker cam 26 (Fig. 6) and the sinker lever 27 were in position on 75 the right, so that, after the sinker cam 26 had been turned through 105° , the sinker lever 27 took up the inward position shown in Fig. 6, and the sinker cam 26 the corresponding position on the left. The sinker 80 draw bar 19 (Figs. 2 and 6), mounted in the swing-head box 13 and connected to the sinker lever 27, is thereby pushed toward the left (Fig. 6). On this sinker draw bar is situated a brake bearing ring 136 (Fig. 85 11) with which is connected a brake 132 sliding in the groove in the sinker bar and engaging, by means of a spring bolt 133, in a recess in the sinker bar. This brake 132 in turn, by means of a nose 134, operates the thread-guide bar 20 (Figs. 4, 11 and 11^a) which carries the thread guide 131. The slurcocks 150 and 151 are also connected to this sinker bar 19 through the bars 117, 118 and driver 137 which slides between the 90 set rings 160 and 161 shown in Figs. 6, 6^a and 6^d, so that a suitable distance is maintained between the slurcocks and the thread guides 131 as is necessary in every stocking frame. In this way, after the shafts 2 and 3 have been turned through 60° , the slurcocks and the thread guide come into position on the left, in which position the thread is laid in the needles of the needle bar 59 (Fig. 11) by means of the sinkers 99, which are lowered by the slurcocks 150 in the known manner. The thread guide is now arrested by the stop 21 (Fig. 4^b) which engages, by means of a pin 21^a in a groove in 95 the thread-guide bar 20. If necessary this stopping of the thread guide can be suitably adjusted by altering the position of the stop 21 by screw 21^a. On the shafts 2 and 3 being rotated through another 30° , the needle bar 59 is drawn back by the cam 53 through 100 the needle bar lever 55 (Fig. 8) by the aid of the draw bar 57, to such a distance that the points of the needles stand close in front of the ware. The work of the presser 74 (Fig. 11) now begins. The presser cam 66 (Figs. 2, 3 and 10) now takes up such a 105 position in relation to the lever 67 (Fig. 10) as to force the presser push bar 72 (Fig. 11) upward by means of the transmission members 68, 69, 70 and 71 (Fig. 11^x), and of the adjustable screw 82 (see Figs. 11^a, 11^c) and to force down the presser 74 by turning it about the pivots 76. The needle points of the needle bar 59 are thereby closed, whereupon the needles continue to retreat a short 110 115 120 125 130 135

distance, so that the old meshes slip down off the closed needles and new meshes are formed. The corresponding position of the members is shown in Fig. 11. The other 5 presser 75 takes no part in the described operation, being out of its working position. There next ensues a further rotation of the shafts 2 and 3 through 45°. At this point, since the falling bar push bar 88 bears, by 10 means of its set screw 113, against the lifting surface 87, the sinkers 99, 100 (Fig. 11) are lifted by the sinker cam 85 (Fig. 11^b) by means of the lever 86. The swing head push bar 92 bears against the heart-shaped 15 member 94, and its set screw 121 lies about $\frac{1}{2}$ an inch above the lifting surface 87, coming into action later while the falling bar 90 receives its forward impulse. The salient portion of the sinker cam 85 (Figs. 9, 20 11^b) has not yet come fully into action, the remainder serving to effect the now ensuing total lift of the falling bar 90 and right swing head when plain one-side goods are being made. In the case of the tubular 25 goods now in question, however, the box 13 is lifted, on which account the set screws 113 and 121 move out of reach of the lifting surface 87 (Fig. 11^c), the lever 86 making an idle stroke. The falling bar and swing 30 head are now operated by the heart-shaped member 94 (which therefore takes over the final function of the sinker cam). This completes the formation of a row of meshes on the needle bar 59. In order that the 35 same series of working operations may be carried out on the opposite side of the machine, it is first of all necessary for the operative members to be returned to the aforesaid bottom position. The heart-shaped 40 member 94 therefore forces the right swing head and the falling bar 90 upward by means of its concentric tracks 107 and 108 which act on the rollers 88 and 92 of the push bars 88 and 92. The anchor 7 and its 45 rollers 10 and 11 (Fig. 4) now again take up the middle position, the anchor 7 being therefore vertical and the box 13 horizontal (Fig. 11^c dotted lines), while the two swing heads and the falling bar take up their 50 highest position. The sinker cam 26 and lever 27 now occupy the position shown in Fig. 6. Consequently, after a total rotation through 180°, the bottom position is again reached, but with the difference that the 55 sinker cam 26, the sinker lever 27, the thread guide 131 and the slurcocks 150 and 151 are now on the opposite side. After being in this second bottom position, the anchor 7 moves toward the left (Fig. 11^c), and the 60 working operation already described is repeated on the other (left-hand) needle bar (60), thus completing a row of meshes in tubular ware. After the shafts 2 and 3 have turned through another 180°, the original bottom position is reached once more, 65

and the series of operations already outlined is repeated in the described manner.

2. *One-side plain goods*.—To make goods on one and the same needle bar (59 or 60) throughout, the rollers 10 and 11 of the anchor 7 (Fig. 4) are pushed along their pivots, thus throwing out of action the change shaft 6 (Figs. 4 to 6) and the heart-shaped member 94 mounted on same. If these rollers 10 and 11 be pushed toward the right, 70 the needle bar 59 is brought into action. The anchor 7 remains in the position facing the shaft and the box 13 rests on the sloping surface 16 of the trestle frame 18 (Fig. 11). If, on the other hand, the rollers 10, 80 11 are pushed toward the left, the needle bar 60 comes into operation. The choice of which of the two needle bars is to be used is therefore open. In this class of work in which, as already mentioned, the heart-shaped member is thrown out of action, the sinker cam 85 (Fig. 9) comes into full use and is not, as in the above described two-side work supplemented by the heart-shaped member 94. The flaps 95 and 96, (Figs. 11^c, 90 11^a, 11^c, 11^d) which are mounted on the member 94 and are allowed a restricted movement of rotation, are opened by the falling bar pusher when the heart-shaped member is stationary, so that the rollers on the falling-bar pusher are able to move away freely. 95

3. *Ribbed goods (reversible goods)*.—When the formation of meshes is to proceed on both rows of needles at the same time, the swing heads remain in one position all 100 the time, that is to say, the loops are made on the same row of needles all the time, as in the case of one-side (plain) goods, while the working out of the formed loops is effected by both needle rows in the manner known in connection with rib machines. Of course, it is also possible to allow the two rows of sinkers to come into operation alternately. The bars 88 and 89 (as well as the bars 92, 93, 72 and 73) are not rigidly connected to the heart-shaped member 94 (Figs. 11^a, 11^c, 11^d) but are merely guided loosely by the slots in this heart-shaped member, in order to prevent them from deviating in any direction. The bars 88, 89, 92, 93 are subjected on the one hand to the action of the heart-shaped member 94, and on the other to the action of the lifting surface 87, on which latter they bear by means of their set screws. Only the curves 107, 108, 95 and 96 of the heart-shaped member act on the rollers (arranged near the lower ends of said bars.) The curved parts 95 and 96 are movable on and bear against the heart-shaped member 94 115 and form a continuation of the outer curved tracks of said member. If one of the rollers of the falling bar pushers is in position within that portion of the heart-shaped member which lies between the said curved 120 125 130

parts 95 and 96, for example the roller of the bar 88 (Fig. 11^x) it would strike against the curved part 96 during the ascent of the bar 88 and be prevented from rising further.

5 This is avoided by the said member 96 turning on its pivot, and itself continuing to move upwardly with the bar 88.

4. *Tickling (narrowing).*—Fig. 12 illustrates the device for tickling, in which the 10 cams concerned are thrown in and out of gear by the displacement (which will be described later on) of the shaft carrying same, as that there comes into position under the cam lever another cam corresponding to the

15 narrowing period. As long as narrowing is not in progress, the two-arm levers 125 and 126 of the parallel shafts 123 and 124, come in contact with a so-called blind cam 129, so that the tickling devices 119 and 120,

20 which are articulated to the levers 125 and 126, remain at rest (Fig. 12). If, however, in place of the blind (circular) cam 129, the tickler cams 127 and 128 are pushed under the lever rollers 125^a, 126^a then the tick- 25 ling device comes into operation. If the box 13 with the swing heads be in the left position, then the tickler device 119 is operated by the cam 127 arranged on the shaft 2; whereas, if the box 13 be in the right hand

30 position, the other tickler device 120 comes into action. The presser cam 66 (Fig. 10) is replaced, during the tickling process, by a blind (circular) cam, represented by dotted lines. The needle-bar cams 53 and 54 (Fig. 35 8) are replaced by cams 138 and 139, shaped in accordance with the narrowing period and a cam 103 (Fig. 9) corresponding to the narrowing period is used in place of the sinker cam 85. The roller standard 46 (Fig.

40 7) is drawn by means of a spring 167 against a chain 162 having links 162^a of a varying height, which runs over a chain wheel 163. This chain is periodically advanced, inasmuch as an operating lever 165

45 with pawl 166 is induced by suitable means, such for instance as a cam or cam shaft, to move a ratchet wheel 164 forward one tooth at a time. If now the shafts 2 and 3 are to be displaced, the roller standard 46 is moved,

50 as allowed by the chain 164, toward the shaft 2, so that the rollers 47 and 48 are able to take up another position in relation to the stepped cams 42 and 43. This displacement of the shafts takes place when the 55 surfaces 44 and 45 (Figs. 7^a and 7^b) of the shaft pusher cams 42 and 43 come into position in the direction of the vertical central line (Fig. 7). On the roller carrier 46 being turned in the direction of the shaft 2,

60 this carrier imparts a slight turning movement to the shaft 40, inasmuch as it moves a lever 49, mounted on same, by means of a stud 49'. By this means a roller 50' on an arm 50 (Fig. 6^a), mounted on the shaft 65 40, is brought into reach of the noses 38, 39

(Figs. 2, 6^a and 6^b) arranged on the coupling member 35. As soon as one of these noses comes into sliding contact with the roller 50' the coupling member 35, and the shaft 2 firmly secured to same, undergo displacement, so that the coupling members 34 and 35 are disengaged and the sinker cam 26 and sinker lever 27 are thrown out of action. The narrowing begins when the sinking of the loops toward the right has been 70 effected after the box 1 has deposited itself on the sloping surface 16 of the trestle frame (Fig. 11). The tickler lever 126 is now lifted by the tickler cam 128 (Figs. 1 and 12), and the tickling device 120 is brought into 75 position for narrowing. After the narrowing—which is well known and therefore need not be more fully described here—is completed, the tickler device 120 retreats, and the box 13 turns on to the side 17 of the 80 frame, so that the other side of the machine is operated. The roller standard 46, which pivots on the axis 12, then swings back and in consequence of the opening of the flap of the heart-shaped member 94, the roller 47 attains its top position, whereupon regular 85 knitting is resumed.

5. The narrowing operation in one-side working—for instance in making a heel—is carried on in the following manner:— 90 The roller standard 46 (Fig. 7) is operated by the aforesaid chain 162 and its roller 47 is brought into engagement with the salient peripheral portion of the shaft-pusher cam 42; and at the same time the roller 48 of the shaft pusher cam 43 ascends into the top position. The cam shafts 2 and 3 are thereby pushed toward the left in such a way that, in place of the ordinary cams, 95 those lying adjacent thereto come into position under all the levers. These new cams are of such shape that they combine the two operations of loop forming and narrowing into one. The machine then works by forming the loops from right to left, followed by narrowing, and then forming loops from left to right, and so on. As the roller standard 46 moves over still farther toward the right, the arm 49 is drawn downward 100 still lower, and the arm 50 (Fig. 6^a) connected to the shaft 40, bears closely against the coupling member 35, so that the sloping surface 39 (Figs. 6^a, 6^b) does not come into operation. The sinker lever 27 and the sinker cam 26 are thrown out of action after 105 each semi-revolution. The box 13 remains continuously on the sloping surface 16 of the trestle frame 18. During this one-side narrowed knitting, the cam holds the tickler device in the top position. In order for 110 this position to be attained, the roller carrier 46 has to depress the yielding slide surface 44 (Fig. 7^b) which springs up again on leaving the roller, thus insuring certainty 115 of action. The operation proceeds in a cor- 120 125

responding manner when working on the other side of the machine.

What I claim then is:—

1. In a knitting machine, the combination with two rows of needles and loop sinking devices adapted to coöperate with each of said rows, of a common support for loop sinking devices of both rows of needles, and means for effecting relative movement between said support and needles to permit the formation of loops on either row of needles, or on said rows alternately, or on both rows simultaneously.
2. In a knitting machine having two needles rows, loop sinking devices for said needle rows, and a frame rotatable about a pivot and carrying said sinking devices whereby the latter may be changed in position in relation to the needle rows for the purpose described.
3. In a knitting machine having two needle rows, loop sinking devices consisting of swing heads, a frame capable of being rocked from one side of the machine to the other upon a pivot and carrying said swing heads, and means to impart movement to the said frame whereby it may be turned over from one needle row to the other, substantially as described.
4. In a knitting machine having two needle rows, in combination loop sinking devices consisting of swing heads, a frame capable of being rocked from one side of the machine to the other upon a pivot and carrying said swing heads, a movable anchor member, cams on adjacent shafts to impart movement to said anchor member, a toothed rack on said anchor member, a shaft, a pinion thereon gearing with said rack, a bell-crank lever on said shaft, and connecting rods attached to said bell-crank lever and the aforesaid frame to rock the latter as the bell-crank lever is rocked by the rack.
5. In a knitting machine having two needle rows, loop sinking devices consisting of swing heads, a frame capable of being rocked from one side of the machine to the other upon a pivot and carrying said swing heads, a movable anchor member, cams on adjacent shafts, rollers on said anchor member engaged by said cams to impart movement to the anchor member, said rollers being capable of lateral movement on the anchor member whereby they may be brought into the path of different operating cams, a toothed rack on said anchor member, a shaft, a pinion thereon gearing with said rack, a bell-crank lever on said shaft, and connecting rods attached to said bell-crank lever and the aforesaid frame to rock the latter as the bell-crank lever is rocked by the rack.
6. In a knitting machine having two needle rows, a swing head for each needle row, a frame capable of being rocked from

one side of the machine to the other upon a pivot and carrying said swing heads, slurcocks in said swing heads, and means to enable the slurcocks to be thrown into and out of action.

7. In a knitting machine having two needle rows, a swing head for each needle row, a frame capable of being rocked from one side of the machine to the other upon a pivot and carrying said swing heads, slurcocks in said swing heads, pushers to actuate the slurcock, bell-crank levers mounted on said frame, a fixed striker with which said bell-crank levers make contact as the frame is rocked from one position to another whereby the slurcock pushers are thrown out of action, substantially as described.

8. In a knitting machine having two needle rows, in combination, a swing head for each needle row, a falling bar in each swing head, an oscillatory member, and push bars intermediate of said member and the falling bars and swing heads whereby the said falling bars and swing heads are raised and lowered by the action of said oscillatory member, substantially as described.

9. In a knitting machine having two needle rows, in combination, a swing head for each needle row, a falling bar in each swing head, a presser for each needle row, and an oscillatory member to effect the raising and lowering of the falling bars and swing heads said member also acting as a sinker cam and throwing the falling bars, swing heads and pressers into and out of action, substantially as described.

10. In a knitting machine having two needle rows, in combination, a swing head for each needle row, a frame rotatable about a pivot and carrying said heads, double cams which rotate in conformity with the rocking movements of the frame, a sinker cam, and means to throw the latter out of action at each half revolution in accordance with the action of the double cams, substantially as and for the purpose described.

11. In a knitting machine having two needle rows, in combination, a swing head for each needle row, a frame rotatable about a pivot and carrying said heads, double cams which rotate in conformity with the rocking movements of the frame, a sinker cam, a coupling, inclined working surfaces thereon, an arm, a roller thereon to be engaged by the aforesaid working surfaces whereby uncoupling is effected to put the sinker cam out of action, substantially as described.

12. In a knitting machine having two needle rows, in combination, a swing head for each needle row, a frame rotatable about a pivot and carrying said heads, cam shafts, double cams thereon which rotate in con-

formity with the rocking movements of the frame, a sinker cam, a coupling adapted when actuated to put said sinker cam out of action, a rocking standard, means to 5 change the position of said rocking standard, connecting means between said standard and the coupling to effect actuation of the latter when the standard is moved, rollers on standards, and cams on the aforesaid 10 cam shafts to coöperate with said rollers

whereby displacement of said shafts is effected, substantially as described.

In testimony whereof I have signed my name to this specification in the presence of two subscribing witnesses.

ALBIN WINKLER.
